UNITED STATES PATENT OFFICE.

MICHEL CRÉMER, OF PARIS, FRANCE, ASSIGNOR TO GENERAL ELECTRIC COMPANY, A CORPORATION OF NEW YORK.

ELECTROMAGNETIC DEVICE.

Application filed March 23, 1922. Serial No. 546,119.

To all whom it may concern:

Be it known that I, MICHEL CRÉMER, a citizen of Russia, residing at Paris, France, have invented certain new and useful Improvements in Electromagnetic Devices, of which the following is a specification.

The electromagnetic device of the present invention has a particular application as a relay for controlling the automatic starting of an electric motor by means of separately actuated electromagnetic switches or contactors, and although not necessarily limited thereto is particularly applicable to the starting of asynchronous motors having a wound rotor. These contactors are controlled by the electromagnetic relay herein-after described. The purpose of this relay as employed in the control of an electric motor is to produce automatically the progressive energization of a number of contactors in a predetermined order, the energization of the contactors proceeding as the decreasing starting current reaches a certain minimum value or in accordance with the acceleration of the motor. Thus the starting operation is always produced at normal torque and the acceleration depends upon the load on the motor.

In the case of induction motors with a wound rotor, it is not practical to start by means of contactors without controlling-relays it being assumed that the potential and the frequency of the rotor circuit are variable. The only practical means consists in the use of acceleration relays, but in the starting systems generally in use, two are generally used, one of which controls the even contactors and the other the odd ones; from this arises a serious complication of the automatic starting outfits, especially when the number of steps is small, since it is necessary, for example, to have two relays to control three contactors.

The system, the description of which is given below, effects the starting as a function of the intensity of an asynchronous motor, controlling any number of contactors through a single and relatively simple relay, the construction of which is based on the following principle:

Instead of two relays, a single one is employed having two different contacts which are closed alternately. One of these contacts supplies the attracting coils of the

even contactors, and the other produces the release of the odd contactors. A series coil which is traversed by the principal current of the stator serves as a minimum-intensity coil; another fine-wire coil, connected to the potential of one phase serves to hold the movable part of the preceding coil and to commute the control-current by connecting it either to the first or to the second group of contactors. Due to this principle, the order of release of the contactors cannot be changed, that is to say, contactor No. 4, for example, cannot be closed before the closure of contactor No. 3.

The characteristic features and the advantages of the invention will be better understood by referring to the following description and drawings:

Fig. 1 represents a sectional elevation of the acceleration relay; Fig. 2 is a diagram of the connections of the relay in the case which applies to the automatic starting of an asynchronous motor with a wound rotor in four steps by means of a controller; Fig. 3 is also a diagram of connections, but modified with a view to a starting equipment for a low-power motor.

Referring to Fig. 1, the relay is composed of two separate magnetic circuits. The magnetic circuit 1 is excited by the series coil 2 traversed by the principal current of one phase of the controlled motor stator. This magnetic circuit is closed by the armature 3 which is pivotally mounted at 4, or by the armature 5 situated behind 3 and which turns about the shaft 6. The regulable springs 7 and 8 tend to release the two armatures. The second magnetic circuit 9, in the form of a U, carries a shunt coil 10, supplied by the voltage of one phase of the source of supply. Its reciprocating plunger core 11 carries at the top a guide-rod 12 of brass, with a regulable stop 13 and, at the bottom, another stop 14. When the coil 10 is supplied with current, the core 11 rises, and since the stop 14 causes the armature 5 to rotate, the latter is brought to a stop, closing the magnetic circuit 1. On the contrary, when the attracting circuit of the coil 10 is broken, the upper stop 13 causes the arresting of the armature 3. The armatures carry two vertical blades with contact fingers 15 and 16, which establish respectively, at the stationary contact 17, the

release circuit of the even contactors, and at the stationary contact 18, that of the odd contactors.

The operation of the relay will now be 5 described, first in case of starting and then in case of stopping.

The diagram of connections of the acceleration relay may be made in several different ways. Fig. 2 represents one of the possible solutions; it is provided for the automatic starting of an asynchronous motor with wound rotor in four steps, by means of a control-switch. Assuming this diagram, the operation is as follows:

15 The line switch 20 being closed, the contactor 21 is energized to close and thereby energize the stator 38 of the motor by closing the control-switch 19. This causes the establishing of the control-circuit through 20 the fuse 25, the auxiliary contact 33 on the contactor 24, the shunt coil 10 of the relay and a protecting resistance 34. At the same time, the motor starts, all the starting resistance being interpolated in the circuit of 25 the rotor 39. The armature 11 of the shunt coil 10 is then attracted, releasing the armature 3, because the stop 13 is lifted; but 3 cannot rotate, notwithstanding the tension of the spring 7, because the starting current 30 produces a strong attraction through the series coil 2 and prevents the release of the armature 3. At the same time the armature 5 is arrested by the stop 14. When the intensity of the current which is passing 35 through the coil 2 has returned to its minimum regulating value, in consequence of the acceleration of the motor, the armature 3 may be released, urged by the spring 7; it rotates, closing the contacts 15—17, and 40 causing the contactor 22 to close. The attracting coil of the contactor 22 is supplied with current through the auxiliary contact 26. When the contactor 22 closes the coil 10 of the relay is short circuited through 45 the auxiliary contact 30 of contactor 23, auxiliary contact 27 of contactor 22 and auxiliary contact 33 of contactor 24. The core 11 consequently falls, and holds by its stop 13, the armature 3. At the same time 50 the contactor 22 short-circuits the connections 35 of the first section of resistances.

The armature 5, which is then released by the stop 14, does not rotate until the current through the winding 2 has sufficiently diminished; after this it rotates to the right and closes, through the contacts 16 and 18, the engaging-circuit of the contactor 23, which has been prepared by the auxiliary contact 28 of the preceding contactor 22. 55 The contactor 23 then closes and short circuits the next rotor resistor by closing the connections 36.

The auxiliary contact 30 of the contactor 23 is opened by the closing of the contactor 23 and breaks the short-circuit around the

coil 10, which is consequently re-excited and its core 11 rises and holds the armature 5 in the attracted position. The relay armature 3 is at the same time released; but it continues to be magnetically held in its position, due to the third point of current intensity which is produced in consequence of the closing of the contactor 23. When the motor current again drops, the armature 3 is released and it closes, through the contacts 15—17, the circuit of attraction of the contactor 24 which has been prepared by the closing of the auxiliary contact 31 of the contactor 23.

The contactor 24, on making engagement, 80 short-circuits, through the connections 37, the entire starting resistance. A maintaining circuit for the contactor 24 is established through the contact 32 and the circuit of the coil 10 is interrupted at the auxiliary contact 33; the relay is then returned to its original position.

For stopping, the control-switch 19 is opened, which operation causes the release of the contactor 21 of the stator. The latter 90 interrupts the circuit of the stator and the control-circuit of all the other contactors.

The regulation of the relay is produced independently for each armature, by means of the springs 7 and 8. Their tension is regulated in such manner that the release of the armatures is effected at a certain minimum starting current, thus causing the starting of the motor as a function of the value of the motor current. If the motor starts at no load, its acceleration is effected mode rapidly, since the points of intensity diminish rapidly; when the motor is loaded the starting operation is effected less rapidly, especially when the motor has to accelerate 100 a large body.

In the preceding diagram each of the contactors 22 and 23 has three supplementary contacts, which is not at all a disadvantage when the contactors are relatively 110 large; but if the starting outfit is provided for a motor of low power and small contactors, it is necessary to reduce the number of these contacts per contactor, in order to simplify the construction. Fig. 3 represents the simplified diagram of control connections which makes it possible to get an automatic starting operation by means of 115 four contactors with the reduced number of supplementary contacts.

The engagement of the contactor 21 (stator) is effected by the closure of the switch 19. The control current passes through the fuse 25, the auxiliary contact 24^a of the contactor 24, and it excites the shunt coil 10 of the acceleration relay which is mounted in series with the protective resistance 34. The core 11 (see Fig. 1) is attracted; the armature 3 consequently is 125 stopped; the armature 3 remains attracted 130

by the coil 2 because of the current taken by the motor on the first starting point. When this starting current diminishes, the armature 3 closes the contacts 15—17, which causes the energization of the contactor 22. Its auxiliary contact 22^A short-circuits the coil 10 and furnishes at the same time the holding current for the contactor, while its second auxiliary contact 22^B prepares the engagement circuit of the contactor 23. The shunt coil 10 being short-circuited, its core falls, releasing the armature 5 of the relay which, after a certain period of lag, is released and which produces, through the closure of the contacts 16—18, the engagement of the contactor 23. The latter is provided with two auxiliary contacts. The two-directions-contact 23^A interrupts to the right; consequently it interrupts the holding circuit of the contactor 22, which is released; it thus breaks the short-circuit of the coil 10 and closes, to the left, the holding circuit of the contactor 23. The contact 23^B prepares for the closure of the contactor 24. The coil 10, which is then re-excited, attracts its core, which releases the armature 3 of the relay. The latter, when the starting current due to the closing of the contactor 23 has been decreased, energizes by the closure of the contacts 15—17, the last contactor 24, the auxiliary contact 24^A of which interrupts the control circuit passing through the coil 10 and the preceding contactors 22 and 23. The auxiliary contact 24^B furnishes the holding current for the attracting coil of the contactor 24. The motor is stopped in the same way as before, by opening the switch 19. This arrangement requires, for each rotor contactor, only two supplementary contacts, which fact simplifies the automatic starting of motors of low power by means of small contactors.

It will be seen that the invention has a particular application in systems in which at least three accelerating resistors and their corresponding contactors are provided, the system being particularly applicable to systems of control having three or more accelerating contactors. In accordance with the provisions of the patent statutes of the United States, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. An electromagnetic device comprising a series electromagnet and two alternately operating switch members, each of which

is movable from one position to a second position under the control thereof, and a shunt electromagnet having a magnetic movable element which moves the said switch members alternately to their first respective positions to be under the control of the series electromagnet and releases the switch members alternately to move to their respective second positions under the control of said series electromagnet. 65

2. An electromagnetic device comprising a series electromagnet and two alternately operated switch members, each of which is movable from one position to a second position under the control thereof, and an alternately energized shunt electromagnet having a reciprocating magnetic element which is connected to the switch member to alternately operate one of the switch members and to hold the same in its respective first position and release the other switch member to move to its respective second position 75 80 under the control of the series electromagnet. 85

3. A relay for controlling electric motors comprising a series electromagnet, a plurality of magnetic movable members biased to the unattracted position controlled thereby, a pair of switch contacts controlled by each of said members, and a shunt electromagnet for alternately holding one of the said pair of contacts at a time in the open position. 90 95

4. A relay for controlling electric motors comprising a series electromagnet, a plurality of magnetic movable members biased to the unattracted position controlled thereby, a pair of switch contacts biased to the closed position controlled by each of said members, and a shunt electromagnet having a magnetic movable member for alternately holding one at a time of said pairs of contacts in the open position and its associated magnetic movable member of the series electromagnet in the attracted position. 100 105

5. An electromagnetic relay comprising a series electromagnet and two pivotally mounted switch members biased to their respective closed positions and movable to their respective closed positions under the control of the series electromagnet, and a shunt electromagnet having a reciprocating plunger, the ends of which cooperate with the switch members for alternately moving one switch member to and holding the same in the open position to be under the influence of the series electromagnet and releasing the other switch member to move to the closed position in accordance with its bias under the control of the series electromagnet. 110 115 120

In witness whereof, I have hereunto set my hand March 7, 1922.

MICHEL CRÉMER.
